UNITED STATES PATENT OFFICE.

JOSEPH A. SKOGLUND, OF ST. PAUL, MINNESOTA.

HEEL LINING FOR SHOES.

Application filed May 12, 1924. Serial No. 712,601.

My invention relates to improvements in heel linings for shoes.

Many wearers of shoes constructed over standard lasts find the heel seats too wide and often too long. Fitting in this manner, the back of a shoe slides up and down and sidewise on the heel, with the result that the wearer is often subjected to discomfort and even injury to the foot, not to mention the 10 damaging wear upon hosiery.

An object of the invention is to supply an inexpensive article of the present nature that may be readily applied to and comfortably worn within a shoe as a heel seat filler.

Another object is to provide an article, as above, the same including an elastic gusset-like back designed to effect the shortening of the shoe and to yieldingly grip the shoe upon a wearer's foot.

With the foregoing and other objects in view, which will appear in the following description, the invention resides in the novel combination and arrangement of parts and in the details of construction hereinafter 25 described and claimed.

In the drawings, Fig. 1 is a perspective view of a heel pocket lining embodying my invention, said view being taken from the front and side of the article; Fig. 2 is a 30 rear elevation of the lining shown in Fig. 1; Fig. 3 is a perspective view showing the article in place within a shoe; Fig. 4 is a longitudinal, central, sectional view also showing the article as applied to a shoe; and Fig. 5 is a perspective view of an alternative 35 form of the invention.

Referring to the drawings, it will be observed that my improvement includes side members 10, a gusset A joining said members at the back thereof and a bottom 11. These parts are seamed together edge-to-edge, as shown, by the modern zig-zag stitch, whereby the lapping of edges is avoided. The outer surfaces of the side members 10 and the under side of the bottom 11 are 40 gummed by being coated with a readily solvent glue of suitable character.

The gusset A comprises an upper section a' and a lower section a² stitched thereto, 45 said latter section like the side members 10 and bottom 11 being of leather or other suitable non-elastic material and gummed on its outer surface with glue or the like. The upper section a' of the gusset A is of surgical or other elastic material.

In applying the lining to a shoe, the glue

on the side members 10, bottom 11, and gusset section a² is moistened and the article pressed in place in the heel seat of a shoe (Fig. 3) with the rear lower portion thereof 60 snugly fitted in the angle at the back of the heel seat. Upon the setting of the glue, the pocket lining becomes a fixed part of the shoe, the side members 10 filling in at the sides thereof.

The upper section a' of the gusset A has a peculiar form, that is to say, it is cut so as to curve forward, at its upper extremity, from the back of the shoe (Fig. 4). This arrangement has the effect of shortening a 70 shoe. Being resilient, however, said gusset section a' yields to the wearer's heel, when his foot is placed in the shoe. Drawing against the heel, particularly at the hip thereof, said gusset section yieldingly grips 75 the shoe upon the wearer's foot and prevents the usual up and down annoying and chafing action of the shoe heel upon the foot.

The alternative form of heel lining shown in Fig. 5 lacks only the bottom 11 of the form first described. This alternate form saves the expense of a bottom piece in those cases, where the bottoms are not desired. This feature is accompanied by another and very important one; viz, the adaptability of the 80 article for trimming at the bottom to suit the same to shoes of different heights. In this connection it will be understood that the lower margins of the side members 10 and gusset A may be cut down to fit a given 85 shoe. The lower section a² of said gusset, being of leather or the like, it may be conveniently trimmed down without impairment thereof. Such would not be the case, 90 however, if the entire gusset were of elastic material and subject to fraying and unraveling when cut inside of a selvaged edge. Said leather gusset section a², further, is particularly advantageous in securely anchoring the 95 lower extremity of the gusset A to a shoe, and especially so, when no bottom is employed in the lining.

Changes in the specific form of my invention, as herein disclosed, may be made within the scope of what is claimed without departing from the spirit of my invention.

Having described my invention, what I claim as new and desire to protect by Letters Patent is:

1. A heel lining for shoes including non-elastic side members and a gusset joining said members at the back, said gusset consist-

ing of a lower section of non-elastic material and an upper section of elastic material.

2. A heel lining for shoes including non-elastic side members and a gusset joining said members at the back, said gusset consisting of a lower section of non-elastic material and an upper section of elastic material, the outer surfaces of said side members and of said lower gusset section being gummed for application to the inner parts of a shoe.

3. A lining comprising a filler pocket for the heel of a shoe, the same including non-elastic side members, an elastic gusset spanning the space between the rear edges of said members to join the same and form the back of the pocket, and a non-elastic bottom, said non-elastic parts being gummed at their outer surfaces for application to a heel seat, the elastic gusset being shaped to shorten the shoe over the hip of the heel and supply a

yielding grip upon the heel of the wearer.

4. A lining comprising a filler pocket for the heel of a shoe, the same including non-elastic side members, a gusset uniting said members at the back thereof and a non-elastic bottom, said gusset consisting of a non-elastic lower section and an elastic upper section, said non-elastic parts being gummed at their outer surfaces for application to the heel seat of a shoe, the elastic gusset being shaped to shorten the shoe over the hip of the heel and thereby supply a yielding grip upon the heel of a wearer.

5. In a heel pocket lining for a shoe, non-elastic side members and an elastic gusset joining said members at the rear edges thereof, said non-elastic members being gummed at their outer faces for application to a shoe.

In testimony whereof, I have signed my name to this specification.

JOSEPH A. SKOGLUND.
